Atty

UNITED STATES PATENT OFFICE.

JAMES W. SNYDER, OF EMPORIUM, PENNSYLVANIA.

CAR-COUPING.

SPECIFICATION forming part of Letters Patent No. 288,270, dated November 13, 1883.

Application filed August 21, 1883. (No model.)

To all whom it may concern:

Be it known that I, JAMES W. SNYDER, of Emporium, in the county of Cameron, in the State of Pennsylvania, have invented new and useful Improvements in Car-Couplings, of which the following, taken in connection with the accompanying drawings, is a full, clear, and exact description.

This invention relates to the class of car-couplings in which the ordinary coupling link and pin are employed.

The invention consists in improved means for guiding the link connected with the draw-bar of one car into the mouth of the draw-bar of the approaching car in the operation of coupling the same, whereby said coupling can be effected with the utmost convenience and safety to the operator.

The invention is fully illustrated in the annexed drawings, wherein Figure 1 is a perspective view of a set of draw-heads provided with my improvements, and showing their position preparatory to coupling them. Fig. 2 is a vertical longitudinal section of the same; and Fig. 3 is a detail view of the cam or adjustable support, by means of which the link is guided into the mouth of the approaching draw-head.

Similar letters of reference indicate corresponding parts.

A represents the draw-head, of the ordinary form. B denotes the coupling-link, and C the usual coupling-pin, which passes vertically through the draw-head and through the link. In front of the coupling-pin C, in the mouth or cavity of the draw-head, is a cam or link-guide, a, in the form of a plate, lying under the link, and projecting upward on opposite sides thereof. Said cam is pivoted in its position by means of manipulating-rods b b, which pass through the sides of the draw-head and are firmly secured to the sides of the cam a. Said manipulating-rods are extended to opposite sides of the car, so as to be convenient of access from either side without the entrance of the operator between the cars. The outer ends of the manipulating-rods are terminated in cranked arms b', which are turned at such an angle and are weighted in such a manner as to automatically retain the cam a, lying

close to the bottom of the interior of the draw-head, and thus leave the entrance into the draw-head unobstructed. By turning the manipulating-rods b b the cam a can be raised to bring the superincumbent link B in range with the mouth of the approaching draw-head preparatory to coupling it therewith, as illustrated in Figs. 1 and 2 of the drawings.

The engagement of the coupling-pin C with the link entering the approaching draw-head, as aforesaid, is effected automatically, as in some other car-coupling devices, and consists in the following instrumentalities: In the cavity of the draw-head is arranged a movable support for sustaining the coupling-pin above the aforesaid cavity, said support consisting of a plate, e, which slides longitudinally in a dovetailed groove, f, in the top of the interior of the draw-head, and is adapted to move across the passage of the coupling-pin, and thus support said pin above the cavity of the draw-head, as illustrated in the annexed drawings. In order to automatically bring the slide e into the position for sustaining the coupling-pin, said parts are connected by a chain, e, and the draw-head is provided with a longitudinal slot, d, for the travel of said chain, the chain being of the requisite length to compel the pin C to draw the slide forward and across the passage of the pin simultaneously with the entrance of the latter into the usual eye, g, in the top of the draw-head. From the under side of the forward end of the slide e projects a pendent pin or lug, h, which the end of the coupling-link of the approaching draw-head encounters, and thereby drives the slide back and causes the pin to drop into the link.

I do not claim, broadly, a link-lifter carried by the draw-bar and adapted to raise and guide the link in making the coupling, as I am aware the same has been used in connection with a draw-bar having the buffer formed by a base extension from the open end of the draw-bar; but in this case the link-lifter extended around the exterior of the draw-bar, and was supported outside of the draw-bar by the projection of the buffer. This arrangement exposes the link-lifter to snow and ice, which are liable to gather on the projecting

buffer, and thus frequently render the same inoperative, whereas by my improvement the link-lifter is housed in the mouth of the draw-bar, and thus protected. Furthermore, I dispense with the extra projection at the base of the draw-bar, which projection, when made to serve as a buffer, exerts undue downward strain on the draw-bar, and is liable to produce breakage of the same or of its fastenings; hence

What I claim as new, and desire to secure by Letters Patent, is—

The combination, with a draw-bar, of the

within-described link-lifter, housed in the mouth of the draw-bar, substantially as set forth and shown.

In testimony whereof I have hereunto signed my name and affixed my seal, in the presence of two attesting witnesses, at Syracuse, in the county of Onondaga, in the State of New York, on this 3d day of August, 1883.

JAMES W. SNYDER. [L. S.]
